UNITED STATES PATENT OFFICE.

WILLIAM D. VANDECAR, OF GRAND RAPIDS, MICHIGAN.

ELECTRIC RAILROAD-SIGNAL.

SPECIFICATION forming part of Letters Patent No. 700,461, dated May 20, 1902.

Application filed June 6, 1901. Serial No. 63,451. (No model.)

To all whom it may concern:

Be it known that I, WILLIAM D. VANDECAR, a citizen of the United States, residing at Grand Rapids, in the county of Kent and State 5 of Michigan, have invented certain new and useful Improvements in Electric Railroad-Signals, of which the following is a specification.

My invention relates to improvements in 10 electric railroad-signals; and its object is to provide means whereby various signals will be automatically displayed to indicate that a given portion of railway-track, known as a "block," is entirely clear of trains, that a 15 train is traversing the same, or that two trains are approaching each other on the same track and within the block.

Another object is to provide means for automatically operating such signals by electricity and to provide the device with certain 20 new and useful features hereinafter more fully described, and particularly pointed out in the claims.

My device consists, essentially, of an electric 25 generator, a main circuit, shunt-circuits to operate the signals and switches, certain and various switches and circuit-closers, and means for operating the same, as will more fully appear by reference to the accompanying drawings, in which—

Figure 1 is a plan of the system for a single block; Fig. 2, a transverse vertical section of the track, a locomotive, and a signal-tower; Fig. 3, a side elevation of a portion of 35 the device, with parts broken away to show the construction; Fig. 4, an enlarged detail, in side elevation, of one of the circuit-closers located in the track; Fig. 5, an end view of the same; Fig. 6, an enlarged detail, in plan 40 view, of the device on the train for operating the circuit-closers; Fig. 7, the same in side elevation, and Fig. 8 a detail of the circuit-closer on the train to operate the bell.

Like characters refer to like parts in all the 45 figures.

A represents any suitable electric generator.

B represents the positive line, and C the negative line, of the primary circuit.

D is a shunt-wire extending from the line

B and branched to form various circuits, as follows: One circuit may pass from the wire D to and through the cut-out E. To open and close the circuit at E, I place a plug E' upon the switch-arm I, from which it is insulated, 55 so that a current of electricity passing over it when in contact with the cut-out E cannot but continue over the wire D' to and through the bulb J, and thence to and over the wire D'' to the negative line C to produce a signal-light at J. A second circuit passes from the wires D, over the wire D', to and through the magnet-coil G, thence to and through the circuit-closer H, and thence to the negative line C, thus completing the circuit. A third circuit 60 passing from the wire D is extended to the terminal F, thence over the switch-arm I when in contact with said terminal, to and over the wire D''' to operate the several signal-lights indicated at J' J'', &c., which are 65 intended to represent colored signal-lights, thence over the wire K'', the switch-arm I', the terminal F' when in contact with said switch, and the wire D' to the negative line C. A fourth circuit passes from the wire D, 70 over the wire D'', to and through the coil G', thence to and through the circuit-closer H', and completes the circuit over the negative line C. A fifth circuit passes from the wire D, over the wire D⁵, to and through the circuit-closer H'', thence to and through coil G'', 75 and thence over the wire D' to and over the negative line C. A sixth circuit may be taken from the positive line B, over the shunt-wire K, to and through the circuit-closer H''', and 80 over the wire D''' to the negative line C. A seventh circuit may be taken from the wire K, over the wire K', to and through the bulb J'', and thence to and through the cut-out E'', when connection is made by means of the insulated plug E' on the switch-arm I', and over the wire D' to the negative line C to produce a signal-light at J''. 85

To avert the danger of confounding any 90 colored lights with ordinary switch-lights, I use a bull's-eye constructed to show two colors—as, for instance, an annular red light with a blue center j', as indicated back of the bulls J' J'' in Fig. 2.

- The switches I and I' are pivotally supported at one end and adapted at the other end to contact the terminals F F' when shifted toward the same, and also have the insulated 5 plugs E' E''' to close the cut-outs E and E''. These switches are provided with centrally-pivoted armatures I'' I''', adapted to oscillate and shift the switches and operated by the electromagnet cores of the coils G G' G'' G'''.
- 10 The circuit-closers H H' H'' H''' have insulated spring-electrodes M and M', arranged at each side of a vertically-movable bolt N, extending upward through the insulated plate S. Vertically adjustable on the bolt N 15 is a plate O, adapted to contact the spring-electrodes M M' and close the circuit of the wires D' D''. Surrounding the bolt N is a spring P, which depresses the bolt N with considerable force. Pivoted to the upper end of 20 the bolt N and engaging the plate S is a cam-lever Q, having a suitable flat face at the bottom and rounded sides, whereby said lever normally assumes a vertical position and when forced to an inclined position pulls the 25 bolt upward and closes the circuit by bringing the plate O in contact with the electrodes M M'. R R are slotted posts at each side of the cam-lever R, which engage the outer ends of the pivot-pin R', connecting the said lever 30 and bolt. These parts assist in keeping the bolt from turning about its axis and also take a part of the strain when the device is operated. To operate these circuit-closers, I provide an adjustable shoe T, pivotally supported 35 in a suitable frame U, attached to a locomotive or car and provided with an arm T', connected to a suitable lever V by a rod V'. A stop-pin T'' prevents this shoe from being lowered too far, and the shoe is so located that 40 when lowered it will strike the levers Q, located near one of the rails, when the train is going one way and the other levers Q when the train is going in the opposite direction.
- Suitably located on the train is an electric 45 bell W, operated by a battery W', to which it is connected by a suitable wire X, forming an electric circuit, in which is a circuit-closer Y, operated by an electric circuit Z. This circuit-closer Y consists of a bell-crank 1, interposed in the circuit and having one arm adapted to close the circuit by contacting a suitable terminal 2 and held out of contact with the same by a pivoted armature 3, having a hook to engage the other arm of the bell-crank and released by an electromagnet 4, having its exciting-coil 5 in the circuit Z. This circuit Z is connected with the track at its negative end in any well-known way, and at the other end is connected to the frame U. 50 To perfect this circuit, the frame U, shoe T, and arm T' are insulated, as indicated at U' on Figs. 3, 6, and 7.
- The electrode M is connected to the track by the wire L.
- 55 The main circuit B C extends the entire length of the series of blocks and may be a

circuit for propelling electric cars or other purposes.

Each block of the road is provided with the system shown in Fig. 1, and each train, car, or locomotive, as the case may be, with the device for operating the circuit-closers located in the track, and may also be provided with the bell and operating appliances shown. If the bell is omitted, then the wires L may be 75 omitted and the electrodes M adjusted to contact the plates O.

The operation is as follows: In the diagram the parts as now adjusted indicate that a train has entered the block from the left and the shoe 80 T on the same engaged the lever Q of the closer H''' and momentarily closed the circuit through the coil G''. This has magnetized the core of said coil and thrown the switch I' to the position shown, contacting the terminal F' 85 and connecting the negative wire K'' of the colored lights J with the negative line C and at the same time cut out the white light J''. This absence of the white light would indicate to a following train that the block ahead 90 was occupied by a train going in the same direction, but the colored lights J' would not show because the wire D''' would still be cut out. When this train leaves the block, it operates the closer H''. This magnetizes the 95 core of the coil G'' and throws the switch I, thus cutting out the negative wire of the colored lights J' and closing the circuit of the white light J''. If a train approaches from the right, it operates the closer H', and this 100 cuts out the white light J and connects the positive wire D''' of the colored lights J'. When this train leaves the block, it operates the closer H. This closes the circuit of the coil G and throws the switch I to the position 105 shown, thus cutting out the colored-light wire D''' and again displaying the white light J. Thus a train going in either direction cuts out the white light behind it while in the 110 block and restores it as it leaves the block, and also while in the block cuts in one side of the colored-light circuit. If when a train 115 is in the block and running toward the right and another train going in the opposite direction enters the block, this latter train would operate the closer H''. This would close the 120 circuit of the coil G' and shift the switch I, thus cutting out the white light J and closing the circuit of the positive wire D'''. Both wires of the colored lights now being connected to the respective main circuit-wires these colored lights will at once be displayed at various points along the line, as indicated at J', and thus every one on both trains 125 would be warned of the danger of a head-end collision. For greater certainty two colored lights may be used in each tower, as shown in Fig. 2, so that if one is disabled the other will show. In like manner if a train was in the block running to the left and a train running oppositely should enter the block the latter would operate the closer H'''. This would 130

connect the negative wire of the colored lights, and said lights would at once be displayed. In the event the bell W is used, whenever the shoe T contacts a lever Q a current will pass 5 through the bolt N, cam-lever Q, shoe T, frame U, and circuit Z, thus magnetizing the core H of the coil 5. This would release the bell-crank 1, close the circuit, and set the bell W ringing, thus indicating that the train 10 had entered a block and suggesting observation of the signal-lights. If for any reason it should become necessary to pass over a circuit-closer without operating the same, the shoe T can be raised by means of the lever V, 15 as shown in dotted lines in Fig. 7.

The circuit-closers shown in the track may be located elsewhere and operated normally, if so desired.

It is obvious that by my device any known 20 electrically-operated signal may be displayed in place of the electric lights shown for use by daylight without departing from my invention.

Having thus fully described my invention, 25 what I claim, and desire to secure by Letters Patent, is—

1. In combination with a block of railway-track, an electric signal at each end of the block, a circuit and cut-out to operate each 30 signal, a series of signals within the block, positive and negative wires to operate the last-named signals, a switch for each end signal to alternately connect the same, and one of the wires for the series of signals, two elec- 35 tromagnets at each switch to oppositely shift the same, electric circuits for each magnet-coil, a circuit-closer adjacent to each end signal and in the circuit operating to open the circuit of said signal and to close the circuit 40 of one of said wires, and a second circuit-closer adjacent to each signal, and in the circuit, operating to close the circuit of the signal at the other end of the block and open the circuit of one of the said wires, and means 45 for operating the said circuit-closers by the passage of a train, substantially as described.

2. In combination with a block of railway-track, an electric signal at each end of the block, an electric circuit to operate each signal, a switch to open and close each circuit, 50 an electromagnet and electric circuit to open each switch, an electromagnet and circuit to close each switch, a circuit-closer in each of the circuits to operate the switches, the two circuit-closers for each signal, being located at opposite ends of the block, substantially as described.

3. In combination with a block of railway-track, an electric generator and positive and 55 negative lines connected to the generator, an electric signal at each end of the block, a shunt-circuit to operate each signal, a series of signals within the block and connected in parallel between a positive and negative wire 60 forming a shunt-circuit, a switch for each end signal adapted to alternately close the end

signal-circuit and the circuit through one of said wires, shunt-circuits operating to shift the switch and close the end signal-circuits, circuit-closers in said circuits each located 70 near the end of the block remote from the respective signal, and shunt-circuits operating to open the end signal-circuit, each being located near the end of the block adjacent to the respective signal, and means for operating the circuit-closers by the passage of trains, 75 substantially as described.

4. In combination with a railway-track, a train, signals, and electric circuits for operating the signals, circuit-closers in said circuits and located near the track, said closers consisting of insulated spring-electrodes, a vertically-movable plate to connect the same, a spring to depress the plate, and a cam-lever connected to the plate, and a shoe on the train 80 adapted to engage the cam-lever and close the circuit, substantially as described.

5. In combination with a block, a train, electrically-operated signals, and electric circuits for operating the signals, an insulated 90 plate between the tracks, insulated spring-electrodes in the circuit and attached to the plate, a vertically-movable bolt, a plate on the bolt, a spring surrounding the bolt and depressing the same, a cam-lever pivoted to 95 the bolt and having a rounded lower end engaging the insulated plate, and a shoe on the train to engage the cam-lever and bring the plate in contact with the electrodes, substan- 100 tially as described.

6. In combination with a track, a train, electrically-operated signals, and electric circuits to operate the signals, circuit-closers in said circuits and located near the track, a shoe on the train engaging and operating said 105 circuit-closers and forming a part of an electric circuit, an electric bell and circuit-closer on the train whereby the bell is caused to ring whenever the shoe contacts a circuit-closer near the track, substantially as de- 110 scribed.

7. In combination with a block of railway-track, an electrical generator, a series of electrically-operated signals at intervals within the block, a positive and a negative wire 115 to operate said signals and each independently connected to the generator, means for connecting and disconnecting each wire to the generator, and operated by the passing trains whereby one wire is connected and disconnected by trains going in one direction and the other wire connected and disconnected by trains going in the opposite direction, sub- 120 stantially as described.

8. In combination with a block of railway-track, an electric generator and main circuit, a series of electrically-operated signals within the block, a line connected to the positive side of the main circuit and to one side of the signals, a line connected to the negative side 130 of the main circuit and to the other side of the signals, and means for closing the respec-

tive lines as a train enters the respective ends
of the block, and means for opening the said
lines as the said trains leave the track, where-
5 by both lines are connected and the signals
operated whenever two trains approach each
other within the block, substantially as de-
scribed.

Signed at Grand Rapids, Michigan, April 19,
1901.
